UNITED STATES PATENT OFFICE.

JOHN W. HOLLIS, OF CINCINNATI, OHIO.

CAR-COUPING.

SPECIFICATION forming part of Letters Patent No. 269,857, dated January 2, 1883.

Application filed October 23, 1882. (No model.)

To all whom it may concern:

Be it known that I, JOHN W. HOLLIS, a citizen of the United States, residing at Cincinnati, in the county of Hamilton and State 5 of Ohio, have invented certain new and useful Improvements in Car-Couplings, of which the following is a specification.

In my improved car-coupling the draw-head tapers toward its outer end, and is provided 10 with a mouth extending from side to side of the head and running about half the length of the same, a horizontal shaft or bolt being passed through the head in the rear of the mouth, which shaft carries the link. This link 15 is made in the shape of a converging loop, bail, or shackle, with an eye at each end, which eyes are traversed by the above-described bolt, while the bend of the link receives all the strain of the coupling-pin of the adjacent draw- 20 head, as hereinafter more fully described, and pointed out in the claims.

In the annexed drawings, Figure 1 is a perspective view of my improved car-coupling, the converging link being shown in its normal 25 or pendent position. Fig. 2 is a plan on a reduced scale, showing the link brought to a horizontal position with one of the lifters and its free end inserted in an ordinary draw-head.

The inner portion, A, of the draw-head is 30 about square in transverse section, and is bored horizontally to receive a short shaft or bolt, B, having at one end a head, C, and at its other end a washer or nut, D. Suspended from this bolt, and adapted to swing freely 35 thereon, is the link E, having two eyes, F F'. This link, instead of running parallel with the sides of the draw-head A, converges toward its center or bend G, thereby affording unusual strength at the part of said link where it pulls 40 against the coupling-pin n of the opposing head N. The outer end of head A has a tapering portion, a, through which passes an ordinary coupling-pin, H. Furthermore, a mouth, I, is provided, running completely across from side to side of the head, and extending back 45 into the square portion A of the same.

Projecting from the end of the car are bearings J for a rock-shaft, K, having at its inner end a crank, L, of such a length as to engage 50 under the link E when occasion requires.

The outer end of this rock-shaft has a handle or lever, M. Located on the opposite side of the draw-head, in bearings J', is another rock-shaft, K', having a crank, L', and lever M', which latter may be provided with a horizontal extension, m'. 55

N is an ordinary draw-head, having a customary coupling-pin, n.

By referring to Fig. 1 it will be seen that the link E F' G, when in its normal position, 60 swings freely from the bolt B, and leaves the top of the draw-head perfectly free and unobstructed. As soon, however, as it is desired to connect with another car, the coupler has only to grasp either of the levers M or M' m' and 65 so turn the shafts K or K' as to cause the cranks L or L' to swing upwardly and lift the link far enough to guide it into the mouth of the opposite draw-head, which entrance is readily effected on account of the converging shape of 70 said link. Now, if the draw-head were of the same width from end to end as the portion A, it is evident the converging link could not be raised far enough to engage with the coupling-pin of the other car; but by tapering or chipping off the sides of said head, as at a, ample 75 clearance is afforded for such a movement of the link.

When the cars are coupled it is apparent 80 all the wear and tear of the pin n is sustained by the bend G of the link, and, as this bend is a solid or unwelded bar, there is no possibility of it breaking or pulling apart. Furthermore, it is apparent that the pull against the head A is accomplished by the eyes F F', that embrace the bolt B, thereby affording a twofold 85 hold of the link, and in case one of said eyes should break the other would still be sufficient to draw an ordinary train.

Another advantage of my invention is seen 90 in the arrangement of the lifting appliances K L M, which, being attached to the end of the car, are not injured in case the draw-head should be detached either accidentally or otherwise. Finally, the chamfered portion of the 95 draw-head may be confined to that part below the mouth I, and the end above said mouth may be extended laterally as far as may be desired to afford a large area of bumping-surface.

I claim as my invention—

1. In combination with a draw-head, A, provided with the chamfered end *a*, the converging link E G, whose eyes F F' take hold of the bolt B C D of said head, as herein described.
- 5 2. The combination, in a car-coupling, of chamfered draw-head A *a*, bolt B C D, converging link E F F' G, and lifting devices K L M, as herein described.

In testimony whereof I affix my signature in presence of two witnesses.

JOHN W. HOLLIS.
